(57) **CLAIM**

The ornamental design for a noise monitor with red surface lighting, as shown and described.

DESCRIPTION

FIG. 1 is a perspective view of a noise monitor with red surface lighting showing the new design.

FIG. 2 is a side view of the design shown in FIG. 1;

FIG. 3 is a bottom view of the design shown in FIG. 1;

FIG. 4 is a top view of the design shown in FIG. 1;

FIG. 5 is a front view of the design shown in FIG. 1; and

FIG. 6 is a back view of the design shown in FIG. 1.

FIG. 7 is a perspective view of a noise monitor with red surface lighting showing another new design.

FIG. 8 is a left side view of the design shown in FIG. 7;

FIG. 9 is a bottom view of the design shown in FIG. 7;

FIG. 10 is a top view of the design shown in FIG. 7;

FIG. 11 is a front view of the design shown in FIG. 7; and,

FIG. 12 is a back view of the design shown in FIG. 7.

The broken line showing of structural features is included for the purpose of illustrating non-claimed subject matter and forms no part of the claimed design.
